UNITED STATES PATENT OFFICE.

MATTHEW BURTON, OF BATAVIA, ILLINOIS.

OIL-CAN.

SPECIFICATION forming part of Letters Patent No. 271,082, dated January 23, 1883.

Application filed May 7, 1881. (No model.)

To all whom it may concern:

Be it known that I, MATTHEW BURTON, of Batavia, in the county of Kane and State of Illinois, have invented certain new and useful 5 Improvements in Oil-Cans; and I do hereby declare that the following is a full, clear, and exact description of the invention, which will enable others skilled in the art to which it app pertains to make and use the same, reference 10 being had to the accompanying drawings, and to letters of reference marked thereon, which form a part of this specification.

My invention consists in a special construction of an oil-can, as hereinafter specifically 15 described and claimed, the cans being portable ones, adapted for domestic uses.

Figure 1 is a perspective view of can, serving to illustrate my invention; Fig. 2, a vertical section; Fig. 3, the same slightly modified. Fig. 4 shows the open-top filling-tube and trap applied to an ordinary oil-can; Fig. 5, a detail.

A, Figs. 1, 2, 3, is a can or vessel of the class having no exterior spout for pouring out, the 25 liquid being forced out therefrom, when wanted, by a pump, either single-acting or double-acting, as preferred, and worked by a lever or not, as desired. The top *b* of the can or vessel is concaved—that is, lower at its center than 30 at its circumference; and it is also provided with a surrounding rim, *c*, to deepen this cup or cavity and prevent any waste or overflow of oil while filling the can or while filling a lamp supported upon the top of the can, the 35 cavity catching and returning all spillings to the can through any appropriate openings in the lamp-support *E*, or in the tube *F* in case the same projects above the top. This support *E* surmounts, or it may form a part of, a fixed 40 open topped conical central tube, *F*, the top or larger opening of which may always remain open, and which serves also as a tube through which the can is filled, and whose lower end terminates in an upwardly-projecting or retro- 45 vated shorter tube or trap, *g*, open at its top, and such that the gas in the can arising from evaporation of the volatile or other fluid contents cannot escape through the trap. Consequently no stopper is necessary for this can, and no

screw-cap cover or equivalent device for closing 50 the inlet.

H represents a force-pump within the can, having an appropriate piston and valve or valves, and the piston may be worked direct by its rod or by the agency of an intermediate 55 lever, *I*, between the piston-rod and the operating-rod *I'*, by which the pump is worked, this lever *I* being hinged or jointed both to the rod *I'* and to the piston-rod.

J is a fixed discharging-tube within the can, 60 extending from the pump to the top of the can, and projecting far enough outside to permit the attachment thereto of a flexible tube, *K*, by stretching the latter over its projecting end, or in any other simple manner, and which is 65 made long enough to reach to the top of any lamp placed upon the stand or support *E*, and then by inserting the free end of such tube into the mouth of the lamp so placed, and upon operating the pump any lamp, (illustrated 70 at *x* in Fig. 1,) is readily filled, and the overflow, if any, is caught by the rimmed concave top and at once returned into the can.

The top of the can may have the rim without the concave. This would prevent waste 75 and would retain any liquid which might be spilled upon the top until it should flow into the can through the open-top tube; but it is better to surround the concave with the rim, as it prevents accidental spattering beyond the 80 can and offers an abrupt boundary-wall, and greatly enlarges the holding capacity of the concave, especially in case the can be recklessly or carelessly overfilled, or in case the lamp should be upset or broken while on top of the 85 can.

The apparatus as above described has no exterior pouring-out spout. It is found to be very successful both as to insuring cleanliness and safety, and also in saving of time and preventing waste of fluid.

The open-top tube for filling the can, in connection with the trap, is adapted for oil-cans of any kind, as will be seen by reference to Fig. 4.

If a double pump be employed, a steadier stream will be obtained.

If the lever *I* be dispensed with, the pis-

ton-rod should be extended directly through the top concave, but at a point at one side of the central stand or lamp-support or open-top tube.

5 I claim—

In combination with an oil-can, the filling-tube in the form of an inverted cone open at its top, terminating at its inner and smaller

end in the retroverted trap-tube *g*, and surmounted with a rimmed perforated lamp-stand, to all substantially as shown and described.

MATTHEW BURTON.
